CALIPER

James C. O'Loughlin, incompetent, Redwood City,
Calif., by Marion F. O'Loughlin, guardian, Red-
wood City, Calif.

Application March 11, 1944, Serial No. 526,024

7 Claims. (Cl. 33—165)

The invention relates to calipers, and particularly to micrometer calipers.

The primary object of the invention is the provision of low cost micrometer caliper for measuring distances beyond the limited range of the fixed frame type of caliper or caliper gage.

Secondary objects include the provision in a long span caliper, of means for setting the spindles in alignment, means for the correction of lateral deviation of the spindles, and means for readily adapting the tool for use over a wide range of dimensions.

The invention possesses other objects and features of value, some of which with the foregoing will be set forth in the following description of the invention. It is understood that the invention is not limited to the showing made by the said description and the drawing as variant forms of the invention within the scope of the appended claims may be adopted.

Referring to the drawing:

Figure 1 is a plan view of the calipers as the tool would appear lying on a bench. Because of the size of the complete figure, a portion of each of the frame arms is omitted.

Figure 2 is a sectional view of the left arm of the caliper, the plane of section being indicated by the line 2—2 of Figure 1.

Figure 3 is a side view of one of the caliper heads, showing both the adjusting rod and the tail spindle in section. The direction from which the view is taken is indicated by the arrow 3 of Figure 1.

In the modern machine shop which handles large and heavy work, securing accurate dimensions within tolerances common in small manufacturing, has posed a problem which increases when measurements of several feet, accurate to thousandths of an inch are required. Accurate devices of high cost are available to the large plant, but for the small shop, make-shift rigs and cut-and-try methods have been the only recourse.

In broad terms the present invention is embodied in a frame comprising two arms, each of which at one end is releasably pivoted to any one of a series of connecting links which are interchangeable to vary the capacity of the caliper. At the other or free end of each arm, a head block is adjustably mounted; and in these blocks are disposed the tail spindle or anvil and the caliper head. Means are provided on one of the frame arms for correcting any lateral deviation which may be found in the alignment of the spindles.

In terms of greater detail, the caliper of the present invention comprises two preferably

curved, flat arms 5 and 6, preferably tapered in width, and each of which is lightened by holes 7 closely spaced along its entire length. The wider end of each of these arms is pivoted between the bifurcated ends 8 of a link 9, the two sides of which are integrally connected by the body or web 11. A set or series of these connecting links is contemplated to give a wide range of usefulness to the tool; and their length between pivotal centers may vary from 3 inches to several feet. For example with 15 inch arms a 3 inch link gives a range up to around 24 inches either inside or outside measurement; a 24 inch link increases the capacity up to around 48 inches; while an 8 foot link would give a capacity from 6 feet to 10 feet.

The links of different lengths are interchangeable; and for that reason the pivot connection between link and arm is preferably secured by means of a screw 12, preferably of the socket head type, threaded into one side of the link so that it may be tightened to rigidly lock the parts together. This construction is shown in the lower part of Figure 3 in connection with another portion of the tool.

At the free or narrower end of the arms are pivotally mounted the head blocks 13 and 14 in which respectively the tail spindle or anvil 16 and the caliper head, generally designated by the reference number 17, are arranged. Each block is bifurcated at the pivoted end and a socket head screw 18 threaded into one side, as shown in Figure 3, completes the connection. Here too, the pivoted joint may be made rigid after adjustment by tightening the screw.

The outer end of each block is preferably rounded over as shown, and bifurcated. The bottom of the bifurcating slot in the block 13 is bored to receive the tail spindle or anvil 16, having its inner end 19 flat, and its outer end 21 rounded, to adapt it for outside and inside measurement as is common practice in micrometer caliper construction. A set screw 22 through the separated ends of the block permits adjustment and rigid fixing of the anvil in place.

In the other block, a similar construction is used, the screw 23 clamping in the head, the sleeve 24 of the caliper head 17. The detail construction of the caliper head forms no part of the present invention since such devices are known; and it is intended that this unit will be secured from the manufacturer of such devices and assembled in the block. It need be pointed out only that the spindle 26 extends through the device to present a flat end 27 on the inside and a

rounded end 28 on the outside; and that the micrometer adjustment by turning the thimble 29 may conveniently cover a range of 1 inch, the capacity of the tool otherwise being obtained by a selected link, and pivotal adjustment at the arm joints.

It should be noted that in each block the clamp screws may be loosened and the spindle reversed, so that in case of need the flat ends 19 and 27 may be on the outside of the tool. This result 10 may also be obtained without disturbing the clamp screws, by swinging the frame arms around on the link, through approximately 180 degrees from the positions shown in Figure 1.

Means are provided for axially aligning the caliper head spindle 26 and the anvil 16. Across the side of each head block is a groove 31, parallel to the spindle axis. The grooves are dimensioned to receive with a close fit, an adjusting rod 32. When the rod is disposed without distortion in the grooves, the axial alignment of the spindles is assured; and since the rod may be several feet long, alignment may be made without bringing the ends of the spindles together.

Lateral deviation in the spindle alignment is unlikely in a carefully made and carefully used tool, but means are provided in one of the frame arms for a minor correction if required.

Interposed in the arm 5, preferably near its connection with the link, is a swivel joint 33, permitting a small amount of twisting adjustment between the parts of the arm. The adjacent ends of the arm terminate in round plates 34 with flat engaging surfaces 36 locked together as best shown in Figure 2, by screws 37 threaded into one of the plates and passing through arcuate slots 38 in the other plate. For stability of the joint, a short stub journal 41 is formed at the center on one of the plates and seats in a bearing in the other plate. Gage marks 42 on the peripheral surface of the plates across the joint between them, mark an aligned setting. Slight adjustment of the swivel joint after loosening the clamp screws 37, will correct small lateral error in the spindle alignment, the complete alignment being obtained with the help of the rod 32 as already explained.

In using the caliper for specific unit measurement, such as for example as 6 feet 2.875 inches the frame is set and aligned to feet and whole inches, the measurement being taken from a gage. The micrometer caliper head is then operated to include the fraction in the final setting. When the tool is used for a relative setting, more or less than a known but unspecified value, such as for example as a cylinder bore .005" more than its piston, the setting of the tool is based directly on the piston and the increase is added by the micrometer setting.

What is claimed is:

1. A caliper comprising a pair of arms, a link for pivotally connecting the arms at their ends, a head block pivotally connected to the other end of each arm, a micrometer anvil arranged in one of the blocks, a micrometer caliper head arranged

in the other block, and means engaging both blocks for axially aligning the anvil and caliper head.

2. A caliper comprising a pair of arms, a link for pivotally connecting the arms at their ends, a head block pivotally connected to the other end of each arm, a micrometer anvil arranged in one of the blocks, a micrometer caliper head arranged in the other block, each of said blocks having a recess therein in alignment with the other when the anvil and caliper head are axially aligned, and an adjustment rod seating in said recesses for aligning the anvil and caliper head.

3. A caliper comprising a pair of arms, a link for pivotally connecting the arms at their ends, a head block pivotally connected to the other end of each arm, a micrometer anvil arranged in one of the blocks, a micrometer caliper head arranged in the other block, a swivel joint in one of said arms for correcting lateral misalignment of the anvil and caliper head in one direction, and means for correcting lateral misalignment of the anvil and caliper head in another direction.

4. A caliper comprising a pair of arms, a link for pivotally connecting the arms at their ends, a head block pivotally connected to the other end of each arm, a micrometer anvil arranged in one of the blocks, a micrometer caliper head arranged in the other block, means engaging both blocks for axially aligning the anvil and caliper head, and means for locking each pivotal connection to render the caliper rigid.

5. A caliper comprising a pair of arms, a link for pivotally connecting the arms at their ends, a head block pivotally connected to the other end of each arm, a micrometer anvil arranged in one of the blocks, a micrometer caliper head arranged in the other block, each of said blocks having a recess therein in alignment with the other when the anvil and caliper head are axially aligned, an adjustment rod seating in said recesses for aligning the anvil and caliper head, and means for locking each pivotal connection to render the caliper rigid.

6. A long-span micrometer caliper comprising a pair of arms, a head block pivotally mounted on one end of each arm, a micrometer anvil arranged in one of the blocks, a micrometer caliper head arranged in the other block, means for axially aligning the anvil and caliper head, and a link detachably and pivotally connecting the other ends of said arms.

7. A long-span micrometer caliper comprising a link having its ends bifurcated, an arm detachably and pivotally mounted in each bifurcated end and movable therein through an arc of about 180°, head blocks pivotally mounted on the free ends of said arms, a micrometer anvil arranged in one of the blocks, a micrometer caliper head arranged in the other block, and means for axially aligning the anvil and caliper head.
